Primary Examiner — Kelley Donnelly(74) *Attorney, Agent, or Firm* — Young Basile Hanlon & MacFarlane P.C.**CLAIM**

The ornamental design for a collapsible shelving unit, as shown and described.

DESCRIPTION

FIG. 1 is a front perspective view of a collapsible shelving unit showing my new design; and, FIG. 2 is a side view thereof.

The features shown in broken lines form no part of the design to be patented.
